MUFFLER FOR INTERCOMMUNICATING
SYSTEM UNITS

William Sinkler Darby, Baltimore, Md.

Application December 27, 1943, Serial No. 515,695

6 Claims. (Cl. 179—1)

This invention relates to intercommunicating devices employed in systems which permit transmission of two-way conversation between a master station and one or more remote sub-stations, and particularly to improvements avoiding transmission of noise from the remote stations to the master station.

Systems of the type described are well known in the art and include microphone-loud speakers usually enclosed in suitable casings or cabinets at each station. The stations are connected by suitable wiring to transmit electrical currents generated by the impact of sound waves on the transmitter. The microphone-loud speaker permits announcement of the message without the necessity for use of a head set or other hearing device. It also picks up a message at the sub-station and transmits it to the master station.

Frequently it is desirable to provide one or more sub-stations in parts of a plant or factory where a medium or high noise level normally exists. In such cases the noise is picked up and transmitted, with the result that the voice sounds are often distorted and therefore unintelligible.

It is the object of the present invention to provide a simple and effective device whereby extraneous sounds such as the noise of machinery and the like can be reduced materially or substantially eliminated from the intercommunicating system without interfering with the facility of use of the system for transmission of conversation.

Other objects and advantages of the invention will be apparent as it is better understood by reference to the following specification and accompanying drawing, in which

Fig. 1 is a view in perspective of a typical remote conversational type sub-station;

Fig. 2 is a plan view of a device adapted to be applied to the sub-station for the purpose of the invention;

Fig. 3 is a section on the line 3—3 of Fig. 2;

Fig. 4 is a section on the line 4—4 of Fig. 2;

Fig. 5 is a view in perspective illustrating a modified form of the invention;

Fig. 6 is a horizontal section through the device as shown in Fig. 5; and

Fig. 7 is an enlarged view of a spring hinge adapted for use in connection with the invention.

In carrying out the invention, I employ means adapted to be associated with the sub-station to muffle extraneous noise and nevertheless permit transmission of the voice to the microphone-loud speaker. The device is arranged to normally permit conversation transmitted from the central

station to be heard without interference. The user may, however, easily muffle the device to prevent the impact of extraneous sounds on the microphone-loud speaker when he wishes to reply to any message received. In a simple form of the device, it may be attached directly to the front of the sub-station. Alternatively the sub-station may be enclosed in a suitable casing embodying the device. In either case, the sub-station is always ready to receive messages which are audible to persons in the vicinity. It may be adjusted by a simple movement to prevent entrance of extraneous sounds when a message is to be transmitted from the sub-station.

Referring to the drawing, 5 indicates a typical remote conversational type sub-station, the details of which form no part of the present invention. It may be provided on its face with openings 6 through which sounds pass to the internal mechanism including the microphone-loud speaker (not shown). Devices of the type described are in common use and are provided in various forms. The invention is applicable to any such devices which are being manufactured and sold for intercommunicating use.

Referring to Fig. 2, I provide a cover 7 which is adapted to be secured by means of screws 8 or other suitable means to the face of the sub-station 5. An opening 9 in the cover is adapted to be closed by a door 10 supported in any suitable manner as for example by hinges 11. The hinges are preferably of the spring type illustrated in Fig. 7, the springs 12 being adapted to hold the door 10 normally in open position. In that position, the face of the sub-station 5 is exposed and sounds produced thereby may be readily heard by persons in the vicinity. Any other convenient means for maintaining the door in open position may be employed. The edges 13 of the door 10 are preferably beveled to afford a more soundproof joint when the door is closed, but this is not essential to the invention.

Near the center of the door I provide an opening 14, and on the face thereof I mount a flared speaking tube 15. The opening 14 may be approximately one inch in diameter, although the precise size is not important. An opening of the size indicated will permit voice sounds to enter without muffling so that the message can be picked up by the microphone-loud speaker and transmitted to the central station. To avoid pickup of extraneous sounds, the user simply pushes the door 10 to its closed position and holds it there while he is transmitting a message. As soon as the door is released, it will return to its

open position so that any message from the central station can be heard readily.

The cover 7 and the door 10 may be made of plywood or any other suitable material. It may be provided with additional sound insulating material if desired, but usually no further insulation is necessary to eliminate the extraneous sounds from the system when the door 10 is closed.

Referring to Figs. 5 and 6, the sub-station 5 is indicated as wholly enclosed within a casing 16 of wood or other suitable material which may have an open bottom so that it is merely dropped over the sub-station. The casing 16 is provided with an opening 17 in its face which is adapted to be closed by a door 18 mounted on hinges 19 similar to the hinges shown in Fig. 7. The door 18 is provided with a speaking tube 20 which communicates through an opening in the door as in the preceding embodiment of the invention, with the interior of the casing 16 and hence with the sub-station which will pick up voice sounds when the door is closed without interference by extraneous noise. When the door 18 is released it will swing open so that messages from the central station can be heard readily.

The precise details as set forth are not essential. The invention comprehends the provision of a muffling device which is normally open and may be closed to prevent access of extraneous sounds to the microphone-loud speaker while permitting voice sounds to be transmitted thereto. Other embodiments of the device adapted to accomplish the purpose of the invention and having the essential characteristics thereof may be utilized.

Various changes may be made, therefore, in the details of the device without departing from the invention or sacrificing the advantages thereof.

I claim:

1. In a communicating system of the type employing a master station and a sub-station, the latter having a microphone-loud speaker to transmit and receive conversation, the improvement consisting of means normally open to avoid interference with messages received and adapted to be manually closed to prevent access of extraneous sounds to the microphone-loud speaker, such means having an aperture with a mouthpiece connected thereto to direct voice sounds to the microphone-loud speaker when said means is closed.

2. In a communicating system of the type employing a master station and a sub-station, the latter having a microphone-loud speaker to transmit and receive conversation, the improvement consisting of a cover for the face of the sub-station having an opening therein, a closure for the opening, means to normally hold the closure in open position to avoid interference with messages received, the closure having an aperture and a mouthpiece connected thereto to direct voice sounds to the microphone-loud speaker when the closure is adjusted to close the opening.

3. In a communicating system of the type employing a master station and a sub-station, the latter having a microphone-loud speaker to transmit and receive conversation, the improvement consisting of a cover for the face of the sub-station having an opening therein, a closure for the opening, resilient means to normally hold the closure in open position to avoid interference with messages received, the closure having an aperture and a mouthpiece connected thereto to direct voice sounds to the microphone-loud speaker when the closure is adjusted to close the opening.

4. In a communicating system of the type employing a master station and a sub-station, the latter having a microphone-loud speaker to transmit and receive conversation, the improvement consisting of a casing adapted to enclose the sub-station having an opening in the face thereof, a closure for the opening, means to normally hold the closure in open position to avoid interference with messages received, the closure having an aperture and a mouthpiece connected thereto to direct voice sounds to the microphone-loud speaker when the closure is adjusted to close the opening.

5. In a communicating system of the type employing a master station and a sub-station, the latter having a microphone-loud speaker to transmit and receive conversation, the improvement consisting of a casing adapted to enclose the sub-station having an opening in the face thereof, a closure for the opening, resilient means to normally hold the closure in open position to avoid interference with messages received, the closure having an aperture and a mouthpiece connected thereto to direct voice sounds to the microphone-loud speaker when the closure is adjusted to close the opening.

6. In a communicating system of the type employing master station and a sub-station, the latter having a microphone-loud speaker to transmit and receive conversation, the improvement which comprises a wall in front of the microphone-loud speaker having an opening of relatively large area to permit free egress of sound waves from the microphone-loud speaker to the atmosphere when messages are being received, a closure for said opening which is normally open to avoid interference with said free egress of the sound waves through said opening but adapted to be manually closed, said closure having an opening of relatively small area whereby the closure, when in closed position, obstructs the greater part of the area of said relatively large opening to prevent access of extraneous sounds to the microphone-loud speaker, and a mouthpiece associated with the small opening in said closure to direct voice sounds to the microphone-loud speaker when the closure is in closed position.

WILLIAM SINKLER DARBY.
